US00D750391S

(12) **United States Design Patent**
Lensing

(10) **Patent No.:** **US D750,391 S**
(45) **Date of Patent:** **** Mar. 1, 2016**

(54) **STOOL WITH TRAY**

- (71) Applicant: **Patrick Lensing**, Van Buren, AR (US)
(72) Inventor: **Patrick Lensing**, Van Buren, AR (US)
(**) Term: **14 Years**
(21) Appl. No.: **29/511,502**
(22) Filed: **Dec. 11, 2014**
